UNITED STATES PATENT OFFICE

130,388

DESIGN FOR A MISSIONARY BANK

Cecil M. Jackson, Pacific Palisades, Calif.

Application February 28, 1940, Serial No. 90,585

Term of patent 14 years

To all whom it may concern:

Be it known that I, Cecil M. Jackson, a citizen of the United States, residing at Pacific Palisades, in the county of Los Angeles and State of California, have invented a new, original, and ornamental Design for a Missionary Bank, of which the following is a specification, reference being had to the accompanying drawing, forming a part thereof.

I claim:

The ornamental design for a missionary bank, as shown.

CECIL M. JACKSON.
